(57) **CLAIM**

The ornamental design for a vehicle top, as shown and described.

DESCRIPTION

FIG. 1 is a perspective view of a first embodiment of the vehicle top of this invention, the vehicle top of this invention shown as mounted to a standard passenger type vehicle; FIG. 2 is a top view of FIG. 1;

FIG. 3 is a left side elevation of FIG. 1, the right side elevation being a mirror image;

FIG. 4 is a front view of FIG. 1; and,

FIG. 5 is a rear view of FIG. 1.

The parts of the vehicles depicted by means of broken lines in the Figures have been shown for illustrative purposes only and form no part of the claimed design.
